Morris Magnier, Phoenixville, Pa., assignor to Rayfel Hosiery Mills, Inc., Phoenixville, Pa., a corporation of Pennsylvania

Application May 3, 1950, Serial No. 9,684

Term of patent 14 years

(Cl. D47—7)

To all whom it may concern:

Be it known that I, Morris Magnier, a citizen of the United States, residing at Phoenixville, in the county of Chester and State of Pennsylvania, have invented a new, original, and ornamental Design for a Stocking, of which the following is a specification, reference being had to the accompanying drawing, forming part hereof.

Fig. 1 is a perspective view of a stocking embodying my new design and Fig. 2 is an enlarged fragmentary section of my new stocking design shown in Fig. 1.

I claim:

The ornamental design for a stocking, as shown.

MORRIS MAGNIER.
